UNITED STATES PATENT OFFICE.

ERNEST G. WAGNER, OF LEWISTON, IDAHO, ASSIGNOR OF ONE-HALF TO MILES D. TAYLOR, OF LEWISTON, IDAHO.

VALVE CONSTRUCTION.

1,169,309.

Specification of Letters Patent. Patented Jan. 25, 1916.

Application filed November 12, 1913. Serial No. 800,634.

To all whom it may concern:

Be it known that I, ERNEST G. WAGNER, a citizen of the United States, residing at Lewiston, in the county of Nez Perce and 5 State of Idaho, have invented a new and useful Valve Construction, of which the following is a specification.

The present invention appertains generally to valves, and aims to provide a novel 10 and improved valve construction.

It is the object of the present invention to provide a valve construction embodying a unique assemblage of parts, in order that the valve may be readily opened, the means 15 for opening the valve being independent thereof, whereby it is impossible for an inexperienced person to jam the valve against its seat, and means also being provided for independently actuating the valve to pulverize or eject any accumulations of foreign 20 or extraneous matter between the valve and its seat.

The present invention also contemplates the provision of a valve construction of the 25 nature indicated, which will be comparatively simple, substantial, durable, compact and inexpensive, as well as simple, convenient and efficient in its use.

With the foregoing general objects outlined, and with other objects in view, which will be apparent as the nature of the invention is better understood, the present invention resides in the combination and arrangement of parts and in the details of construction 35 hereinafter described and claimed, it being understood that changes in the precise embodiment of the invention herein disclosed, can be made within the scope of what is claimed, without departing from the 40 spirit of the invention.

The invention has been illustrated in its preferred embodiment in the accompanying drawing, wherein the figure is a longitudinal central section of the valve construction.

45 In carrying out the invention, there is provided a cylindrical body or casing 1, preferably in the form of a casting and which has one end open. The body or casing 1 is provided with a lateral inlet port 50 2 adjoining its open end, and with an opposite lateral discharge port 3 adjoining the other end, the body or casing being provided with an inner annular rib or collar 4 intermediate the inlet and outlet ports and form-

ing a contracted opening smaller in diameter 55 than the open end of the casing.

Driven into or secured within the annular rib or collar 4, is a valve seat 5 of suitable material, the same being preferably provided with a conical or beveled face at that 60 side adjoining the inlet 2.

A cap 6 is threaded or otherwise engaged over the open end of the body or casing 1 and a relatively long guide sleeve 7 has one end threaded outwardly through a central 65 tap provided in the cap 6, the guide sleeve 7 projecting axially into the body or casing 1 to a point near the valve seat, and having a counter bore or socket 8 in its outer end, forming a stuffing box in which suitable 70 packing 9 is disposed. A gland 10 is threaded into the stuffing box 8 to compress the packing.

A smooth stem or spindle 11 is freely slideable and rotatable through the gland 10 and 75 the guide sleeve 7, and is equipped with a valve 12 at its inner end, between the valve seat 5, the face of the valve being preferably conical or beveled about its margin, to seat 80 against the face of the valve seat in an effective manner. The valve stem 11 is slideable through the guide sleeve 7, to permit the valve to be seated by the pressure of the fluid entering the inlet port 2, the valve 85 being of the check valve type.

The outer end of the valve stem 11 is squared or otherwise formed, as at 13, for the engagement of a suitable handle or lever 14, in order that the valve may be rotated 90 and forced inwardly, to pulverize or eject any accumulation between the valve and its seat.

As a means for opening or unseating the valve, a relatively long plug 15 is threaded 95 inwardly through the closed end of the body or casing 1 and projects to a point near the valve seat, and a spindle or screw 16 is threaded through the plug 15 so that its tip or inner end is adapted to be projected 100 through the valve seat and abut against the face of the valve through the seat 5, the outer end of the spindle or screw 16 being preferably provided with a hand wheel 17. The plug 15 is provided at its outer end 105 with a reduced extension 18, upon which a cap 19 is threaded to provide a stuffing box in which is disposed suitable packing 20,

the packing being compressible against the spindle or screw 16 by means of the cap 19.

The present valve construction may be employed in divers capacities, such as, for 5 attaching a sprinkling hose to a fire hydrant for a blow-off for steam boilers, and the like. It will be evident that when the inlet port 2 is connected with any fluid supply, the pressure of the fluid will normally 10 seat the valve 12, that is, when the screw 16 is retracted. To open the valve, it is merely necessary to run the screw 16 inwardly, which will force the valve from its seat against the pressure of the fluid, in order 15 that the fluid may flow through the annular valve seat and out the discharge port 3. The valve being of the check valve type, will close automatically when the screw 16 is retracted, it being noted that the valve can- 20 not be jammed against the valve seat through the medium of the screw 16, which will render it impossible to injure the valve or its seat by inexperienced persons. This is of importance, inasmuch as the jamming 25 of a valve against its seat often results in the destruction or mutilation of the valve or its seat, which is of disadvantage in other respects.

Although the valve cannot be forced 30 against its seat, through the medium of the screw 16, the valve may be forced inwardly and rotated properly through the medium of the valve stem 11 and its handle 14, in order that any sediment or accumulation between 35 the valve and its seat, can be pulverized or ejected. The valve stem 11 being smooth and unthreaded, will prevent the valve, however, from being jammed with excessive force against the valve seat, the valve being 40 released, as soon as the pressure is relieved from the valve stem.

From the foregoing, taken in connection with the drawing, the other advantages and capabilities of the present device will be apparent to those versed in the art, and need 45 not be itemized at length, it being observed that the objects aimed at have been carried out satisfactorily.

Having thus described the invention, what is claimed as new is:—

In a valve construction, a cylindrical casing having one end open, a lateral inlet port adjoining the said end, a lateral outlet port adjoining the other end, and an inner annular rib intermediate said ports and forming a contracted opening smaller in diameter than said open end of the casing, a cap engaged over the open end of the casing, a valve seat fitted within said rib, a relatively long plug threaded through the other end 60 of the casing, a relatively long guide sleeve threaded through the cap, a valve disposed between the valve seat and cap and seatable against the valve seat, the valve having a smooth stem slideable and rotatable freely 65 through the guide sleeve, a valve unseating screw threaded through the said plug and adapted to be projected through the said valve seat and abut against the valve, and packing means carried by the outer ends of 70 the said plug and sleeve and embracing the screw and valve stem, respectively, said plug and sleeve projecting to points near the valve seat.

In testimony that I claim the foregoing 75 as my own, I have hereto affixed my signature in the presence of two witnesses.

ERNEST G. WAGNER.
